Primary Examiner — Holly E Thurman*Assistant Examiner* — Kristopher Michael Blechschmidt(74) *Attorney, Agent, or Firm* — NOD Law PC(57) **CLAIM**

The ornamental design for a combined knife and sheath, as shown and described.

DESCRIPTION

FIG. 1 is a left, front, top perspective view of a knife and sheath;

FIG. 2 is a right, rear, bottom perspective view of a knife and sheath;

FIG. 3 is a rear elevation view of a knife and sheath;

FIG. 4 is a front elevation view of a knife and sheath;

FIG. 5 is a right elevation view of a knife and sheath;

FIG. 6 is a left elevation view of a knife and sheath;

FIG. 7 is a top view of a knife and sheath; and,

FIG. 8 is a bottom view of a knife and sheath.

The regularly spaced broken lines in FIGS. 1-8 illustrate portions of the combined knife and sheath that form no part of the claimed design.

1 Claim, 7 Drawing Sheets(56)
